[57] **CLAIM**

The ornamental design for a soap holder, as shown and described.

DESCRIPTION

FIG. 1 is a front, top and side perspective view of the soap holder showing my new design, the bar being fixed to the looped handle and being pushed frontwise into the bottom or top of a bar of soap whereby a bar of soap can be held by the looped handle;

FIG. 2 is a front elevational view thereof, the rear being a mirror image of the front shown in FIG. 2;

FIG. 3 is an end elevational view thereof, the end opposite being a mirror image of the end shown in FIG. 4;

FIG. 4 is a top plan view thereof; and,

FIG. 5 is a bottom plan view thereof.

FIG. 1

FIG. 2

FIG. 3

FIG. 4

FIG. 5
